DRILLING MACHINE

John Wesley Lee, Dayton, Ohio, assignor, by
mesne assignments, to General Motors Corpora-
tion, Detroit, Mich., a corporation of Delaware

Application May 31, 1932, Serial No. 614,317

14 Claims. (Cl. 77—26)

This invention relates to improvements in con-
tinuative drilling machines.

It is among the objects of the present invention
to provide a drilling machine which requires
the services of an operator for workholder load-
ing purposes only.

Another object of the present invention is to
provide novel workholders which cooperate with
the operating drills to hold the workpieces in
place, and which permit the drilled workpieces to
fall off by gravity as soon as the withdrawing
drills clear the just drilled holes.

Another object of the present invention is con-
tinuously to move the workholders through a pre-
determined cycle, whereby each workholder passes
a loading station, then moves through part of
said cycle where a drill performs its operation,
then passes an ejecting station and finally re-
turns to the loading station again to start an-
other cycle.

Another object of the present invention is to
provide a mechanism for automatically stopping
the machine in case a drilled workpiece becomes
stuck in its workholder.

Further objects and advantages of the present
invention will be apparent from the following de-
scription, reference being had to the accompan-
ying drawings wherein a preferred embodiment
of one form of the present invention is clearly
shown.

In the drawings:

Fig. 1 is a side elevation of a drilling machine
embodimenting the present invention.

Fig. 2 is a top view of the same.

Fig. 3 is a cross sectional view taken on the
line 3—3 of Fig. 1.

Fig. 4 is a fragmentary sectional view looking
in the direction of arrow 4 in Fig. 5.

Fig. 5 is an enlarged fragmentary sectional view
taken on the line 5—5 of Fig. 4.

Fig. 6 is an enlarged sectional view taken on
the line 6—6 of Fig. 4.

Fig. 7 is a fragmentary elevation looking in
the direction of arrow 7 in Fig. 2, the main frame
of the machine being partly broken away for bet-
ter disclosure of the safety stop.

Fig. 8 is a sectional view taken on the line
8—8 of Fig. 3.

Fig. 9 is an enlarged fragmentary sectional view
taken on the line 9—9 of Fig. 3.

Fig. 10 is a chart illustrating progressive steps
of a drilling operation which takes place during
one complete circular movement of a workpiece.

Referring to Figs. 1 and 3 a base 20 supports
a main frame 25, which is of substantially cylin-

drical form and has a main reinforcing rib 26
providing an annular recess 27 substantially cen-
tral of the main frame 25. Supported on said re-
inforcing rib and located in the annular recess
thereof is a hollow cylindrical bracket 28 which
function will be described presently. A rotary
platform or carriage 30 is slidably supported on
an annular track 31 provided by main frame 25
and carries a bushing 32 in its annular boss 33,
which bushing is journaled about the cylindrical
exterior surface of the hollow bracket 28, thus
providing for rotation of the carriage 30 about
the center of said cylindrical member 28. Mount-
ed upon the carriage 30 centrally of its axis of
rotation is a generally cup shaped bracket 40
which slidably supports a plurality of drill spin-
dles supporting casings 41. As best shown in Fig.
2, six of such casings have been chosen which
are guided for radial movement on the bracket
40 in equiangular spaced relationship by V-shaped
guide members 42 which are secured to bracket
40 by screws 43. It is deemed sufficient to state
that each of the drill spindles 44 is journaled
in ball bearings located in the casings 41 and that
each spindle is prevented from longitudinal move-
ment relative to its casing. Any suitable chuck
45 drivingly connects a drill 46 with each drill
spindle 44.

Bracket 40 which is rotatable with the carriage
30 comprises a plurality (in the present instance
six to correspond with the number of drills) of
arms 50 each of which terminates into a block 51
which receives a cylindrical bushing 52 having its
axis vertical. A screw 52a threaded into each
block 51 maintains each bushing in position. The
inside diameter of the bushing 52 is just big enough
to slidably receive a cylindrical workpiece *a* as
can be seen in Fig. 4. The drills 46 are adapted
to cut a hole into a workpiece which axis is at
right angles to the axis of the hole. The drill 46
as shown in Fig. 3 is performing a cutting opera-
tion and it is obvious that the bushing 52 and the
drill cooperate to maintain the workpiece in proper
position without any further provisions. The slot
53 in the bushing 52 permits chips to fall off.

100

Mechanism for continuously rotating drill spindles

Referring particularly to Figs. 2, 3, 7 and 8, a
motor 60 is shown mounted on the base 20 in any
suitable manner. A shaft 61 journaled in suitable
bearings provided by reinforcing ribs 62 and 63
of the main frame 25 is drivingly connected with
the armature shaft 64 of motor 60 by a coupling
65. Located in the reinforcing ribs 62 and 63 are
taper roller bearings 66 and 67, respectively, for

110

rotatably supporting a shaft 68 which is parallel to shaft 61 and prevented from longitudinal movement in either direction by a collar 69 integral with shaft 68 and resting against roller bearing 67, and 5 a washer 70, resting against the other roller bearing 66 and secured to shaft 68 by a nut 71 which is threadedly received by the end of said shaft. Shaft 68 is drivingly connected with shaft 61 by meshing gears 68a and 61a carried by the ends of 10 shafts 68 and 61, respectively. The shaft 68 carries intermediate the reinforcing ribs 62 and 63 a worm 72 which is in mesh with a worm gear 73 keyed as at 74 to a hollow spindle 75 which is supported for rotation about the axis of the cylindrical bracket 28 by taper roller bearings 76 and 77, located in said member. A nut 78 threadedly received by the lower end of spindle 75 maintains the worm gear 73 in engagement with a shoulder 79 of spindle 75. The end of spindle 75 which extends beyond bearings 76 carries a bevel gear 80 which is held in position by a nut 81 threadedly to the end of spindle 75. Worm gear 73 and bevel gear 80 which are both fast on spindle 75 together prevent said spindle from longitudinal movement 25 in any direction relative to the cylindrical bracket 28. Vertically below each drill spindle casing the bracket 40 provides a recessed boss 82 which provides bearings 83 and 84 for spindles 85 and 86 respectively, to which a gear 87 and 88 respectively, is keyed, each one of which is also located in the recess of the boss. These two gears are in mesh with each other and gear 87 is in mesh with a gear 89 which is keyed to the overlying drill spindle 44 as at 90. The free end of the spindle 86 30 which extends beyond boss 82 has keyed thereto a bevel gear 91, which is in mesh with bevel gear 80, the thrust of the bevel gear 91 which is determined by the intermeshing angle of the bevel gears is taken up by a thrust bearing 92 which rests against 40 the boss 82.

Mechanism for rotating the platform

In the present instance the carriage 30 which carries the drill spindle casings 41 and the work-holding bushings 52 is adapted to rotate so that each workpiece after having been inserted into one of the bushings 52 in a loading station A (see Fig. 2) moves through a complete circular path while the drilling operation takes place and returns to loading station A again. Pressfitted over the annular boss 33 of movable carriage 30 and concentric of the axis of rotation of the latter is a ring gear 100 which is furthermore drivingly connected with the platform by dowel-pins 101 as best shown in Fig. 3. This ring gear meshes with a smaller gear 102, keyed to a shaft 103 and retained in position thereon by a nut 104 which is threaded over the upper end of shaft 103. This shaft is rotatably supported in bearings 105 and 106 provided by a boss 107 of the main reinforcing rib 26 of main frame 25. The gear 102 rests on a thrust bearing 108 which in turn rests against boss 107. A regular Johnson clutch 109 is adapted to transmit rotary motion from the motor to the shaft 103. This clutch is well known to those skilled in the art, no detailed description or illustration of the same is therefore deemed necessary. It is sufficient to state that a worm gear 110 is loosely mounted on shaft 103 and is fast with the driver of the Johnson clutch, the driven clutch part is firmly mounted on shaft 103 and upon movement of a clutch collar 109a from the position in Fig. 3 to that in Fig. 7 both clutch parts are in driving engagement. Worm gear 110 is in mesh 70 with a worm 111, keyed to a shaft 112 (see also

Fig. 8) which is journaled and prevented from longitudinal movement in any direction by suitable bearings (not shown) provided by the reinforcing ribs 62 and 63 of the main frame 25. Shaft 112 is drivingly connected with shaft 61 by meshing gears 112a and 61b carried by the shafts 112 and 61, respectively.

80

Referring more particularly to Figs. 3, 7 and 8 there is shown a hand lever 115 outside the main frame 25 which is keyed to a shaft 116, journaled in the main frame 25. Keyed to shaft 116 inside the main frame is a lever 117 which biased end 118 pivotally receives a link 119 which is also pivoted to the biased end of a lever 120, mounted on a shaft 121 which is journaled in bearings (not shown) provided by the reinforcing ribs 62 and 63 of main frame 25. Intermediate its bearings this shaft has keyed thereto as at 122 a clutch collar shifting lever 123 which is in permanent operative engagement with clutch collar 109a. When the operator rocks the hand lever 115 from the dot and dash position to the full line position in Fig. 7 the Johnson clutch 109 transmits motion from the motor to the shaft 103, and when rocking hand lever 115 in the reverse direction the clutch will be disengaged as can be readily understood.

85

Mechanism for moving drill spindle casings radially when platform rotates

90

Referring particularly to Figs. 3 and 9, a disc 130 is slidably supported on an annular track 131 provided by the bracket 40 for rotation about the axis of rotation of the carriage 30. The disc 130 provides a recess 132 in which is located a cam ring 133, fastened to the disc 132 by screws 134 and located within said recess by a dowel pin 135. Recess 132 and cam ring 133 together form a cam groove 136 which receives anti-friction rollers 137 each of which is carried by a block 138, connected with a drill spindle casing 41 by a screw 139 and spaced therefrom by a collar 140, interposed between said block and the drill spindle casing. The cam groove 136 naturally has to be stationary in order to effect radial movement of the moving drill spindle casings. The periphery of the cam disc 130 is provided with gear teeth 130a which are in mesh with a plurality of equally spaced gears 141 each of which is mounted on a spindle 142 journaled in bearings 143 and 144 provided by bosses 145 of the bracket 40. To the lower end of each spindle 142 is attached a gear 146 having the same number of teeth and the same pitch diameter as the gears 141. Each one of the gears 146 meshes with a ring gear 147 which is secured centrally of the axis of rotation of the carriage 30 to bracket 28 by screws 148 and dowel pins 149. Gear 147 is of the same pitch diameter and has the same number of teeth as the gear represented by the toothed cam disc 136. As will appear from the foregoing, toothed cam disc 130, gears 141 and 146 and gear ring 147 constitute a planetary gearing which maintains cam disc 130 stationary in spite of its support on the rotary 140 bracket 40.

100

Means for definitely locating workpieces in bushings until drills operatively engage workpieces

As has been expressed earlier, the bushings 52 merely slidably support a workpiece which is not sufficiently definite to locate a workpiece relative to the operating drill. As best shown in Figs. 2, 4 and 5 an arcuate track for the workpieces in the bushings is provided by a bar 150

105

110

115

120

125

130

135

140

145

150

secured by screws 151 and nuts 152 to a cylindrical frame 153 which telescopes with the main frame 25 as at 154 and rests against an annular shoulder 155 of the latter as may be seen in Fig. 3. As long as the workpieces in the bushings slide over bar 150 they are definitely located and by the time they passed the bar the drills have already operatively engaged them which makes a dislocation of the workpieces impossible. The engagement of each drill with an aligned workpiece takes place in a predetermined position during a complete revolution of the carriage 30 as governed by the cam groove 136.

16 *Workpiece ejecting after drilling operation*

The cam groove 136 which determined the drill engaging position for each workpiece during its circular movement also determines the point of disengagement of a drill from a workpiece. In Fig. 2 there is shown a station B in which under cam action each drill will disengage from its workpiece whereupon the latter drops onto a chute 160 which is formed by a rake-like structure 161 as shown in Fig. 4; this structure is fastened in any suitable manner to a bracket 162 which in turn is secured to frame 153 by screws 163. One workpiece after the other drops onto said chute when moving past station B. The chute then guides the workpieces outside of frame 153 from where they drop into any suitable receptacle, (not shown).

17 *Safety stop*

Referring more particularly to Figs. 2, 4, and 7, a stop member 170 is keyed to a stub shaft 171 which is journaled in a bearing provided by a boss 172 of the frame 153. Keyed as at 173 to stub shaft 171 is a lever 174 which, by a link 175 is connected with hand lever 115. When the machine is in operation, that is, when hand lever 115 is in the full line position as shown in Fig. 7, stop member 170 is obstructing the path of a properly located workpiece in a bushing 52. The workpieces which are moving in the direction of arrow C in Fig. 2 normally drop onto the chute 160 in position B, should however for one reason or another one of the workpieces become stuck in its bushing then the lower part of the workpiece will during the movement of the bushing between station B to loading station A engage and rock stop member 170 clockwise as viewed in Fig. 7, thereby moving the hand lever 115 from the full line position to the dot and dash position in Fig. 7 whereby the Johnson clutch will be disengaged and rotation of the platform 30 will cease.

18 *Chip removing means*

Referring to Figs. 3 and 6, the frame 153 provides an annular pocket 180 into which the chips fall. The annular pocket of frame 153 communicates with a chute 181 also provided by said frame which leads into a pocket 182 provided by the main frame 25. Bracket 40 carries a plurality of horizontally extending bars 183 to each of which is attached a plate 184 which fits into the annular pocket 180 and is adapted to convey accumulated chips therein to the chute 181 from where they drop into pocket 182. A chip conveyor 185 is adapted to convey assembled chips in pocket 182 to any suitable removable receptacle (not shown). A lower sprocket wheel 186 is rotatably mounted on the biased end of a lever 187 which is pivotally mounted on the inside of the pocket 182 as at 188. A stop screw 189 extending laterally through said pocket is normally engaged by the lever 187,

thus allowing for clockwise rotation of the lever 187 only, as viewed in Fig. 1. An endless conveyor, including resilient metal bands 191 and rectangular fragments 192, is guided over sprocket wheel 186 and another sprocket wheel 193 which is rotatably supported adjacent the mouth 194 of the pocket 182. Rotatable in unison with sprocket wheel 193 is another sprocket wheel 195 which through a chain 196 is drivingly connected with a sprocket wheel 197, attached to a shaft 198 in any suitable manner, which shaft is journaled in bearings provided by cylindrical bosses 199 of a casing 200 mounted on main reinforcing rib 26 of main frame 25 by screws 201. Mounted on shaft 198 and located within the casing 200 is a helical gear 202 which meshes with another helical gear (not shown) carried by a shaft 203 journaled in a bearing provided by a boss 204 of main reinforcing rib 26 of main frame 25. The upper end of shaft 203 carries a gear 205 which is in constant mesh with the ring gear 100 on the carriage 30. Gear 205 rests on a thrust bearing 206 which in turn rests against boss 204. Shaft 203 is herewith held against longitudinal movement downwardly as viewed in Fig. 3; longitudinal movement of shaft 203 upwardly is prevented by the helical gear mounted thereon which thrust is directed downwardly as viewed in Fig. 3. It appears from the foregoing that the chain conveyor is moving in the direction of arrow 207 (see Fig. 1) as long as the carriage 30 rotates, thereby carrying accumulated chips in the lower part of pocket 182 along the surface 208 and discharging them through mouth 194.

19 *Cooling system for drills*

A cooling and lubricating medium such as soap and water is applied to each drill. As best shown in Fig. 3, a stationary pipe 210, connected at one end with a water pump (not shown) is connected with its other end to a flanged fitting 211 which rotatably supports a cup shaped member 212 which in turn threaded receives a hollow plug 213. Plug 213 and member 212 are interlocked in properly adjusted position by any suitable means. A packing 214 is interposed between fitting 211 and plug 213 so as to prevent soap water from escaping between member 212 and fitting 211, respectively plug 213. A plurality of pipes 215 (in the present instance 6 conforming with the number of drills) communicates with the hollow chamber of plug 213 and are threaded into said plug. The other ends of the pipes 215 communicate with faucets 216 which are threaded into the bushing carrying blocks 51. Soap water is pumped from a supply (to be described) through pipe 210 into the hollow chamber of plug 213 and then through pipes 215 and faucets 216 from where it escapes and flushes the drills 46. The used soap water flows into pocket 182 from where it overflows through a sieve 220 into a receptacle 221 formed by the base 20 which is divided into two separate receptacles 221 and 222 by a reinforcing rib 223. The pump which is preferably driven by motor 60 delivers soap water from the supply in receptacle 221 to the pipe 210. The faucets 216 may be regulated to adjust the spouting velocity of the soap water and thereby give the water spout a desired direction as can be readily understood.

20 *Lubrication of machine*

In order to properly lubricate the various moving parts of the machine a lubricating system is provided which will be described presently. Re-

80

85

135

140

145

150

ceptacle 222, provided by the base 20, contains a supply of lubricant 230. A suitable pump 231 attached to a reenforcing rib 25a of the main bracket by screws 231a communicates with the lubricant supply through a pipe 232 carrying an oil filter 234 which dips into the lubricant supply. Pump 231 is drivingly connected with shaft 61 by a gear 235 of the pump which meshes with gear 61a. A pipe 236 which extends through the hollow spindle 75 and cam disc 130 has its lower end connected with the pump 231 and its upper end with a flanged fitting 237, which rotatably supports a cup-shaped member 238, which in turn threadedly receives a hollow plug 239. Interposed between said hollow plug and the flanged fitting is a packing 240 which prevents lubricant within the hollow plug from escaping between said plug and the cup-shaped member 238, respectively, the flanged fitting 237. A plurality of pipes 241 (in the present instance six) communicate with the chamber within plug 239 and are threadedly received by said plug. The other ends of said pipes are connected with elbows 242 also threadedly received within ducts 243 of the bracket 40. Short pipes 244, threaded with one end into the ducts 243, terminate adjacent apertures 245 in carriage 30. Lubricant will be pumped from the supply through pipe 236, plug 239, pipes 241, ducts 243, and short pipes 244, from where the lubricant flows through apertures 245 in the carriage 30 onto the annular track 154 of the main bracket 25 thus providing for proper lubrication between said track and the sliding carriage. The lubricant leaves the track through ducts 246 and flows through vertically aligned ducts 247 from where it drains onto worm gear 110 which carries lubricant to the intermeshing worm 111, thus providing for proper lubrication of this worm gearing. The lubricant finally returns to the receptacle 222 only to be circulated again in the just described manner. Some of the lubricant in pipe 236 flows through a hole 250 in said pipe into ducts 251 and 252 from where the lubricant flows onto bevel gear 80, through ducts 253 in cylindrical bracket 28, past lower roller bearing 77 onto wormgear 73 from where the lubricant returns to receptacle 222.

Mode of operation

The machine is started to operate by starting the motor 60 and shifting handlever 115 from the dot and dash position into the full line position as viewed in Fig. 7. Running of the motor alone results in rotation of the drills 46, running of the water pump and lubricant conveying pump, while the manipulation of the handlever 115 in the above described manner effects driving engagement of the Johnson clutch whereby the carriage 30 with all the parts carried thereby commences to rotate. The operator is standing adjacent loading station A as indicated in Figs. 2 and 10 and inserts workpieces into the bushings which move between loading station A and station A1. During such movement of the bushings the drills are withdrawn from the interior cylindrical walls thereof but the underlying rail 150 cooperates with the bushings to properly locate the workpieces until the drills operatively engage the same, which takes place in position A1 as governed by the shape of stationary cam groove 136. For better understanding the cooperation between one bushing and one drill during one complete circular movement of the same will be described detailedly, it being understood that such cooperation exists between any other bushing and

cooperating drill during one complete circular movement of the same. Suppose the operator just inserted a workpiece into a bushing in station A (see Fig. 10), the same will be carried by the bushing in counterclockwise direction as viewed in Fig. 10 and will slide on top of rail 150 until the drill operatively engages said workpiece in position A1 and advances under cam action into the same at a uniform rate of speed. The advancing of the drill continues until the workpiece reaches position A2 in which position the drill 46 has completed the drilling operation. Retraction of the drill takes place when its cam roller 137 follows the descent 136a. As soon as the retracting drill clears the workpiece in position A3 the same will drop through its bushing and onto chute 160 from where it falls into any suitable receptacle. The empty bushing then moves into position A again, ready to receive another workpiece which during another complete circular movement of the bushing is drilled in exactly the same manner as just described. Should for one reason or another a finished workpiece become stuck in its bushing the workpiece will engage and rock member 170 which throws the hand lever 115 from the full line position into the dot and dash position as viewed in Fig. 7, whereupon the carriage 30 ceases to rotate as explained earlier.

While the form of embodiment of the present invention as herein disclosed, constitutes a preferred form, it is to be understood that other forms might be adopted, all coming within the scope of the claims which follow.

What is claimed is as follows:

1. A machine for drilling a hole in a workpiece comprising, in combination, a rotatable carriage; a plurality of drill spindles supported by and guided for movement relative to the carriage; a plurality of workholders supported on the carriage in alignment with the drill spindles, each of said workholders being adapted to support a workpiece in the direction of movement of the aligned drill spindle only and to prevent rotation of the same about the axis of said drill spindle and permitting its removal by gravity; means for preventing the removal by gravity of a workpiece in a workholder only until the aligned drill starts to cut into said workpiece; means for moving the drill spindles toward the workpieces in response to rotation of the carriage; and means for withdrawing the drill spindles from the workpieces after a drilling operation.

2. A machine for drilling a hole in a workpiece comprising, in combination, a rotatable carriage; a plurality of drill spindles supported by and guided for movement relative to the carriage; a plurality of workholders supported on the carriage in alignment with the drill spindles, each of said workholders being adapted to support a workpiece in the direction of movement of the aligned drill spindle only and to prevent rotation of the same about the axis of said drill spindle and permitting its removal by gravity; means for preventing the removal by gravity of a workpiece in a workholder and properly locating said workpiece relative to an aligned drill only until said aligned drill starts to cut into said workpiece; means for moving the drill spindles toward the workpieces in response to rotation of the carriage; and means for withdrawing the drill spindles from the workpieces after a drilling operation.

3. A machine for drilling a hole in a workpiece comprising, in combination, a rotatable carriage; a plurality of drill spindles supported by and

piece from a workholder only until the aligned drill commences to cut into said workpiece; a prime mover; a manually shiftable clutch for drivingly connecting the carriage with the prime mover; and means operated by a stuck workpiece in a workholder for shifting the clutch into disengaged position.

11. A machine for drilling a hole in the periphery of a prismatic workpiece comprising, in combination, a rotatable carriage; a plurality of drill spindles supported on the carriage and guided for movement relative thereto; a plurality of workholders supported on the carriage in alignment with the drill spindles, each of said workholders being adapted to support a workpiece with its axis substantially vertical and permitting its removal by gravity; means for moving the drill spindles toward and away from the workholders in response to rotation of the carriage; a stationary chute being so located that after the withdrawal of the drills from the workpieces the same drop off the workholders and into said chute; a stationary track slidably supporting the lower end of the workpieces in the workholders thereby locating the workpieces in a predetermined position relative to the aligned drill spindles only until the drills operatively engage the workpieces, the lower end of the workpieces projecting in such position beyond the workholders; a prime mover; a shiftable clutch for drivingly connecting the carriage with the prime mover; and a manually operable clutch shifter rod, said rod having a portion intermediate the chute and the stationary track which projects into the path of the extending portion of a stuck workpiece in a workholder and which when engaged by said extending portion shifts the clutch shifter rod into clutch disconnecting position.

12. A machine for drilling a hole in a prismatic workpiece comprising, in combination, a rotatable carriage; a plurality of drill spindles supported on the carriage and guided thereon for horizontal movement relative thereto; a plurality of substantially vertical bushings supported on the carriage in alignment with the drill spindles, said bushings being open at both ends for vertically slidably supporting workpieces; stationary means for moving the drill spindles relative to the carriage and the workpieces in the bushings in response to rotation of the carriage; means for

80 withdrawing the drills from the workpieces after a drilling operation; and means for supporting the workpieces in the bushings only until the drills start to cut into said workpieces.

13. A machine for drilling a hole in a workpiece comprising, in combination, a machine frame comprising an annular track and an annular pocket communicating through a chute with a deeper chip receiving pocket of the machine frame; a carriage rotatable on said annular track; a plurality of drill spindles supported on the carriage and guided thereon for movement relative to the carriage; a plurality of workholders supported on the carriage in alignment with the drill spindles and vertically above the annular pocket; means for moving the drill spindles toward the workholders in response to rotation of the carriage; means for withdrawing the drill spindles from the workholders after a drilling operation; a plate attached to the carriage and projecting into the annular pocket, said plate being adapted to move accumulated chips from said pocket to the chute; a conveyor for removing chips from the deeper pocket to the outside of the machine; and means for operating the conveyor in response to rotation of the carriage.

14. A machine for drilling a hole in a workpiece comprising, in combination, a machine frame comprising an annular track and an annular pocket communicating with a descending chute; a carriage rotatable on said annular track and including annularly and concentrically arranged gear teeth; a plurality of drill spindles supported on the carriage and guided thereon for movement relative to the carriage; a plurality of workholders supported on the carriage in alignment with the drill spindles and vertically above the annular pocket; means for moving the drill spindles toward or away from the workholders in response to rotation of the carriage; a plate projecting into the annular pocket and movable therein in order to convey accumulated chips from said pocket to the chute; a movable endless conveyor adapted to convey the chips falling through said chute away from the machine, said endless conveyor including a plurality of sprocket wheels meshing with said conveyor; and means including a train of gears driven by the teeth of the carriage for driving one of said sprocket wheels.
